United States Patent Office

Des. 186,354
Patented Oct. 13, 1959

186,354

COMPOSITE FABRIC

Della K. Forster, East Lansing, Mich.
Application June 27, 1957, Serial No. 46,760

Term of patent 14 years
(Cl. D92—1)

The figure is a plan view of a composite fabric showing my new design.

I claim:

The ornamental design for a composite fabric, as shown.
